COMBINATION CLOTHESLINE SUPPORT
AND LAWN ORNAMENT

George E. Nitschke, Toledo, Ohio

Application March 23, 1946, Serial No. 656,732

2 Claims. (Cl. 211—119.17)

1

This invention relates primarily to a clothes line support and particularly to one which serves a dual purpose by being transformable into an attractive lawn ornament when not set up for wash day service.

The principal object of my invention is the provision of such a structure which may readily be changed from a clothes line support to a lawn ornament.

Another object of my invention is the provision of a device which is simple and sturdy in design and one which may be manufactured easily and at low cost.

A further object of the invention is the provision of a supporting structure having a main vertical post built in two telescoping sections, the lower or base post being hollow to receive the upper section in its lowered position and the upper section having hinged horizontally extending arms which swing downwardly along the upper post section so that they may also be received within the lower post section.

A still further object of my invention is the provision of automatically acting latching means for holding the upper post in its upwardly extended position and such a latch which is effective in any of the rotationally variant positions the upper and base post sections may be telescoped together.

Another object is the provision of a hexagon shaped lower or base post section and an upper post member being H shaped in cross section, whereby the open sides of the member may receive the laterally extending arms when folded downwardly in their collapsed position.

Other objects and advantages of the invention will become apparent upon reading the following description with reference to the accompanying drawing in which:

Figure 1 is a side elevation of a structure embodying my invention arranged in extended form in proper position to support clothes lines.

Figure 2 is a similar view of the same structure in its compact form wherein the upper post member is telescoped entirely within the lower base section except for the ornament holding plate and the ornament at its top, depicted here as a large silvered globe;

Figure 3 is a vertical section of the top end of the upper post member with the side arms in their collapsed position;

Figure 4 is a horizontal section through both post parts taken on the line 4—4 of Figure 1;

Figure 5 is a horizontal section through the upper post member and the lower ends of the arm struts taken on the line 5—5 of Figure 1;

2

Figure 6 is a vertical section taken on the line 6—6 of Figure 1 through the side arm at the point where its supporting strut is pivoted; and

Figure 7 is a side elevation of the top end of the upper post member with a sun dial mounted thereon to demonstrate a possible alternate article to replace the silvered globe of Figures 1 and 2.

As shown in Figure 1 the base post member 1 is embedded in concrete through which it extends slightly into ordinary soil 3. This is considered desirable in order that any water reaching the interior of the post will not be confined there to rust the metal by the concrete blocking the end.

The base post 1 is preferably hexagon shaped and is hollow so as to receive, in sliding but non-turning relation, the upper post section 4 as shown in Figure 4. The post member 1 may be rectangular or octagonal and still be adaptable to receive section 4 in several positions if any of these shapes are preferred for other reasons. Post section 4 is formed of two U channels welded together back to back. Near its lower end is a latch 5 mounted with its center of gravity on the outer side of the pivot pin 6. In this way the

latch 5 is always inclined to fall outwardly to catch over the upper end of base post 4 when the upper section is raised into its extended position as shown in Figure 1.

At the top of post section 4 is a plate 7 which may be bolted in place through the depending portions of the angle members 8 to which it is welded as shown in Figure 3.

The outer edge of plate 7 extends beyond the periphery of post extension 4 so that it will engage the upper end of base post 1 when these two post sections are telescoped together. Supported from the top end of post extension 4 are arms 9 hinged at 10. These carry conventional hooks 11 to which clothes line may be fastened. Pivoted at 12 to the arms 9 are struts 13, on the lower ends of which are button headed studs 14. These slide into bayonet slots 15 cut into one side of post extension 4 to hold the arms 9 in their horizontal extended position as shown generally in Figure 1 with the detail brought out in Figure 5.

When it appears that the structure will not be needed as a clothes line support for a while, the clothes line may be removed and the arms 9 swung downwardly by withdrawing struts 13 from the bayonet slots 15. Both the arms and the struts hang within the laterally facing openings of the H shape of the post extension 4. The arms 9 are U-shaped in cross section and are of sufficient size to fit snugly at their hinged ends 10 between the parallel sides of post extension 4.

The struts 13 are flat straps and are held along one side of the arms 9 by bushings 16 on the pivot pins 17 as may be noted in Figure 6. By this, positional interference between the hooks 11 and the struts 13 is avoided when both are lodged within the confines of the openings of post extension 4.

Post extension 4 is then raised slightly so that latch 5 may be unhooked from the edge of base post 1 and swung inwardly to permit extension 4 to drop within base member 1. In order to provide an air cushion to prevent upper post 4 from dropping too rapidly down into base post 1, fastened to the bottom of the upper post is a hexagon plate 18 designed to conform to the interior shape of the base post 1. The fit should be sufficiently close to let the air by at a slow rate. With the angular arms and struts concealed, and height of the post reduced fifty per cent the structure becomes compact and much more sightly. With an appropriate ornament mounted on the top it is an attractive addition to the grounds. As outside clothes line supports are ordinarily used only one day a week during pleasant weather and not at all during winter months or when the weather is bad, most of the time this device may be left in its ornamental position. The part of the yard where it is located may then be used without embarrassment for lawn furniture and game equipment for the entertainment of guests. Instead of being a structure to be screened with shrubbery the clothes line support has thus become a decorative feature of your grounds of which you may be proud.

While one specific embodiment of the invention is herein shown and described, it will be understood that various changes in the size, shape and arrangement of parts may be made without departing from the spirit of the invention.

What is claimed is:

1. In a combination clothes line support and lawn ornament a stationary hollow post of polygonal cross section, an extension member nonrotatively and telescopically mounted within the post, laterally raisable arms pivotally mounted near the top of the extension member, supporting means for holding the arms in their lateral position, means on the outer ends of the arms to which clothes lines may be fastened, and overhanging plate means on the top of the extension member for keeping the member from dropping below the top end of the post and also for providing a support for a decorative article.

2. A device as set forth in claim 1 in which the extension member is H-shaped in horizontal cross section and the ends of the legs of the H fit into corners between the sides of the polygonal post.

GEORGE E. NITSCHKE.
